(57) **CLAIM**

The ornamental design for a body for hanging light fixture, as shown and described.

DESCRIPTION

FIG. 1 is a side view of the body for hanging light fixture;

FIG. 2 is a side view of the body for hanging light fixture offset from the view of FIG. 1 by an angle of thirty degrees; and,

FIG. 3 is a top view of the body for hanging light fixture, when the bottom view of the lighting fixture element is identical.
